LAST LATHE

Laurence E. Topham, Wenham, Mass., assignor to
 United Shoe Machinery Corporation, Flemington, N. J., a corporation of New Jersey

Application September 4, 1943, Serial No. 501,276

3 Claims. (Cl. 142—15)

This invention relates to last lathes of the type shown in United States Letters Patent No. 2,072,228, granted March 2, 1937, upon application of L. E. Topham et al., and is particularly concerned with the improvement of such lathes in respect to the accuracy of the results obtained when cutting last foreparts and heel parts separately.

As stated in the said patent, the length grading has, in the past, given considerable trouble when foreparts and heel parts were made separately in a machine of this type, and the patented machine was designed to overcome the length grading errors which had previously occurred when using a single model wheel to control the cutting of lasts of more than one size from a given model. This was accomplished by so shifting the mounting of the model wheel that the leading edge of the model wheel, instead of the front point thereof, would come to the length grading center for the model wheel side of the machine when the corresponding portion of the cutter reached the length grading center for the cutter side of the machine. This produced correct overall length but caused an error in the width grading which had not previously existed, when the front points of the model wheel and cutter were correlated, with the result that the faces of the two last parts which abut at the joint in the last were not identical in size and shape and, consequently, the outer surfaces of the last parts would not be flush at the joint.

It is a primary object of the present invention to provide a last lathe of the type under consideration in which graded foreparts and heel parts of two-part lasts can be produced with accuracy in respect to overall length without sacrificing accuracy in width grading and identity of the abutting faces of the last parts at the joint.

With this object in view, I correlate the front point of the model wheel with the analogous point on the cutter, thus producing the abutting faces of the two last parts of the same size and outline so that they will match perfectly, and correct the error in the overall lengths of the last parts by providing means for automatically modifying the length grading factor during the cutting operation by an amount just sufficient to cancel the said error. In the embodiment illustrated herein, I employ cam operated mechanism for shifting the length grading handle, with which the lathe shown in the aforesaid patent is provided, progressively as the cutting of the last part proceeds, the cam being so designed that the right amount of compensation is effected regardless of the length of the model. The cam,

as shown, is driven from the feed screw, which effects translatory movement of the cutter carriage, through a reduction gear of such ratio that the cam does not make more than one revolution during the traverse of the cutter over the longest block to be cut.

Another object of the invention is to provide mechanism which will grade up or down with substantial accuracy two or more $\frac{1}{2}$ sizes, instead of only one $\frac{1}{2}$ size, each way, while using the same model wheel. This results in a reduction in the number of different model wheels necessary and the frequency with which it is necessary to change them as compared with the machine of the patent, in which it is practicable to grade up or down only one $\frac{1}{2}$ size while using a given model wheel.

This object is readily accomplished by proper design of the aforesaid cam, by which any required magnitude of correction of the length grading error can be obtained at any stage in the cutting operation and can be distributed lengthwise of the last part as desired.

The length grading error which the present mechanism is designed to correct consists in "over grading" i. e., when grading up, without changing model wheels, the machine without the present invention produces a last part which is too long, and when grading down from the model it produces a last part which is too short. By my novel compensating mechanism the effect of the grading mechanism in the lathe may be progressively diminished, while the cutting of the last part proceeds, by an amount sufficient to neutralize the overgrading effect of using a model wheel which is too thick or too thin. The cam may be so designed as to modify the grading factor to any desired degree and, consequently, to eliminate the over grading error through a range of two or more $\frac{1}{2}$ sizes up and down from the model.

These and other features of the invention, comprising certain novel combinations and arrangements of parts, will be apparent from the following description of a preferred embodiment of the invention shown in the accompanying drawings, in which,

Fig. 1 is a view in elevation of the left-hand end of the machine, illustrating the novel apparatus of the present invention;

Fig. 2 is a view in front elevation of the left-hand portion of the machine;

Fig. 3 is a plan view, showing the essential features of the organization;

Fig. 4 is a diagram, showing the relation of different model wheels to the length grading center for the model side of the lathe; and

Fig. 5 is a vertical section on the line V—V of Fig. 2.

The invention is illustrated as applied to and embodied in the lathe of Letters Patent No. 2,072,228 hereinbefore referred to. Reference may be made to that patent for a more complete showing of details of the lathe structure which are not modified by the present invention. In the following description reference numerals in parentheses refer to analogous parts in the machine shown in the patent.

The machine has a main frame 10 (10) with longitudinal slideways on which slide a cutter carriage 12 (16) and a model wheel carriage 14 (18). These are driven by a right- and left-hand screw 16 (20) which turns in the direction indicated by the arrow in Fig. 1 and engages nuts mounted in the carriages 12 and 14. The nut mounted in the model wheel carriage 14 is provided with gear teeth engaging a rack 18 (28) which is used for length grading purposes.

The model wheel carriage carries a model wheel 20 (76) mounted in a holder 22 affixed to the carriage and the cutter carriage carries a cutter 24 (78) by which the last block being turned is shaped.

The model 26 and the block 28 are mounted to face in opposite directions on the axis 30 (74) about which they rotate when a block is being cut. The length grading mechanism is best shown in Fig. 3. The length grading is effected by moving the sliding rack 18, which turns the nut in the model wheel carriage 14, and this movement of the rack is accomplished by a block 32 (110) which is pivoted to the rack and slides on an inclined guide 34 (112) as the carriage 14 moves toward the right or left, carrying the rack 18 with it. The guide 34 is mounted on a plate 36 (114) pivoted at 38 on the frame 10 and is angularly adjusted by a gear segment 40 (118) pivoted at 42 on the frame and linked to the plate 36 at 44, 46. The segment is adjusted by a worm 48 on a shaft 50 operated by a length grading handle 52, shown in Figs. 1 and 2. All of the foregoing is substantially as shown and described in the aforementioned Letters Patent. In the patented machine adjustments are made manually for grading up or down from the model by turning the length grading handle 52 toward the left or right, as the case may be, the handle then being locked in adjusted position and left untouched while a last block is being turned.

For the purpose of the present invention it is necessary to change the adjustment of the length grading mechanism, thus to modify or diminish its action, to correct the length grading error hereinbefore referred to, while the model wheel is traversing a model and a last block is being cut. To this end, a pinion 54 is secured to the left-hand end of the shaft 56 of the feed screw 16, as shown in Figs. 1 and 3, and a gear 58 is journaled to rotate freely on a stationary stud 60 mounted on the machine frame 10 in position for the gear to mesh with the pinion 54. Keyed to the gear 58, to rotate therewith on the stud 60, is a cam 62 which is engaged by a cam roll 64 upon the upper end of a cam lever 66.

The lever 66 forms a part of a rigid rocker member comprising said lever, a shaft 68, a bar 70, and a casting 72 which, as shown in Fig. 2, extends laterally in the form of an arm 74. The

shaft 68 is journaled in stationary bearings 76, 78 supported by the machine frame.

The ratio of the gearing 58, 54 is three to one and the said gearing constitutes a reduction gear between the feed screw 16, which effects translatory movement of the cutter carriage 12, and the cam 62. The pitch of the screw 16 is such that the cutter carriage is advanced one inch during each twenty degrees of rotation of the cam and, consequently, eighteen inches during one complete revolution of the cam so that the cam does not have to make more than one revolution during the traverse of the cutter over the longest block to be cut.

At the right-hand end of the arm 74, and preferably integral therewith, is a cam-slotted plate 80 (Fig. 2) having three slots 82, 84, 86 therethrough. The plate 80 is located directly behind the length grading handle 52 which contains a spring-pressed pin 88 having a knob 90 by which the pin may be pulled outward against the tension of the spring. When the knob is released the spring presses the pin inward toward the plate 80 and if the pin is moved into register with any one of the slots 82, 84, 86 it will enter the same.

From an inspection of Fig. 2 it may be seen that the slots 82 and 86 are so disposed that if the plate 80 is swung about the axis of the shaft 68 while the pin 88 is in one of said slots the length grading handle will be swung about the axis of the shaft 50, turning that shaft and modifying the grading effect by shifting the inclined guide 34. The slot 84 is so disposed that it is approximately concentric with the shaft 68 and if the pin 88 be engaged in this slot, which is its correct position for zero grade, the swinging of the plate 80 will have no appreciable grading or grade modifying effect.

As in the patented machine, a disk 92 is secured to the front end of the length grade adjusting shaft 50 and the length grading handle 52 is carried by a crank arm 94 journaled loosely upon said shaft. A binding screw 96 passing through an arcuate slot 98 in the disk 92 is threaded into the end portion of the crank arm 94 which is opposite to the handle 52 and serves normally to clamp the crank arm firmly to the disk, while permitting relative angular adjustments to be made if required.

From the foregoing it will be apparent that when the feed screw 16 is rotated to impart translatory movement to the cutter and model wheel carriages 12 and 14 the cam 62, which is driven by the feed screw, will be rotated and that the cam slot plate 80 will be swung about the axis of the shaft 68. If the pin 88 is in either of the slots 82, 86, the length grading handle 52 will be turned to an extent and in a manner determined by the shape of the cam path in the cam 62, instead of said length grading handle remaining immovable as it would do if it were inserted in one or the other of holes 100, 102 in a stationary disk 104 with which the patented machine is provided.

The model wheel assemblies each comprise a model wheel 20 mounted in an individual holder 22 and are so designed that the front points of all model wheels will come to the length grading center for the model wheel side of the machine when the corresponding point of the cutter comes to the length grading center for the cutter side of the machine. This is partially shown diagrammatically in Fig. 4 wherein 20A and 20B indicate two model wheels of widely different thicknesses, both being shown in neutral position with their front points on the axis 30 of the model at the

length grading center G for the model side of the machine as they are when the corresponding point of the cutter 24 is at the length grading center G' for the cutter side of the machine. Since the machine is so constructed that when the parts are in this position the pivot of the block 32 and the pivot 38 are collinear and adjustment of the length grading segment 40 will cause no movement of the rack 18 and the nut operated by it, last foreparts and heel parts turned under control of the same model wheel from models that fit each other will be identical in size and shape at the length grading center, which is coincident with the joint in the last, and will, therefore, fit each other perfectly.

Having described the invention, what is claimed is:

1. In a last lathe, a cutter carriage, a model wheel carriage, a rotating feed screw engaging said carriages and effecting translatory movement thereof, power driven means for grading up and down by changing the relative movement of the model wheel carriage and the cutter carriage, including manually operated means for setting the grading means for different grades, a rotary cam geared to the feed screw, and connections between the cam and the grade setting means whereby the setting of the latter is automatically changed within a selected grade during movement of the carriages.

2. In a last lathe, a cutter carriage, a model

wheel carriage, a rotating feed screw engaging said carriages and effecting translatory movement thereof, power driven means for grading up and down by changing the relative movement of the model wheel carriage and the cutter carriage, including manually operated means for setting the grading means for different grades, mechanism geared to the feed screw, and connections between said mechanism and the grade setting means whereby the setting of the latter is automatically changed within a selected grade during movement of the carriages.

3. In a last lathe, a cutter carriage, a model wheel carriage, a rotating feed screw engaging said carriages and effecting translatory movement thereof, power driven means for grading up and down by changing the relative movement of the model wheel carriage and the cutter carriage, including manually operated means for setting the grading means for different grades, a rotary cam, reduction gearing connecting the cam to the feed screw whereby the feed screw makes a plurality of revolutions during one revolution of the cam, a cam lever in cooperative engagement with the cam, and connections between the cam lever and the grade setting means whereby the setting of the latter is automatically changed within a selected grade during the movement of the carriages occurring during one revolution of the cam.

LAURENCE E. TOPHAM.
